Primary Examiner — Laura Davison(74) *Attorney, Agent, or Firm* — TraskBritt(57) **ABSTRACT**

A playing card handling device comprises a card storing area that supports a stack of playing cards, the card storing area having a playing card support surface. A card removing system removes playing cards individually from the bottom of the stack. A pivoting arm is automatically moved by a motor between at least two positions, wherein in a first position the end of the arm opposite a pivot is disengaged from a playing card at the top of the stack and in a second position the end of the arm is engaged with a playing card at the top of the stack. A processor in the playing card handling device directs movement of the pivoting arm between at least the first and second positions when a predetermined number of cards is present in the card storing area. Methods of card handling include employing the use of such a pivotal arm.

PLAYING CARD HANDLING DEVICES

This application is a continuation of U.S. patent application Ser. No. 15/892,698, filed Feb. 9, 2018, now U.S. Pat. No. 10,926,164, issued Feb. 23, 2021, which is a continuation of U.S. patent application Ser. No. 14/939,462, filed Nov. 12, 2015, now U.S. Pat. No. 9,901,810, issued Feb. 27, 2018, which is a continuation of U.S. patent application Ser. No. 14/077,035, filed Nov. 11, 2013, now U.S. Pat. No. 9,220,971, issued Dec. 29, 2015, which is a continuation of U.S. patent application Ser. No. 12/943,871, filed Nov. 10, 2010, now U.S. Pat. No. 8,579,289, issued Nov. 12, 2013, the disclosure of each of which is hereby incorporated herein in its entirety by reference.

TECHNICAL FIELD

The present invention relates to playing card handling systems, particularly card handling systems for shuffling devices that may be used in a casino or card club environment, and particularly playing card shuffling devices that individually move a lowermost card in a stack from one area of the card handling system to another area of the card handling system.

BACKGROUND

Known card feeding systems in a card handling device may include a support surface with pick-off roller(s) that are located within the support surface to remove one card at a time from the bottom of a vertically oriented stack of cards. In this orientation, each card face is in a substantially horizontal plane with the face of a card contacting a back of an adjacent card. The weight of a stack of cards ordinarily provides a sufficient force against the rollers to assure proper movement of most of the cards. But as the stack size decreases after most of the cards have been delivered, the weight of the cards may no longer be sufficient, especially with the last few remaining cards in the stack to assure proper movement of the cards.

U.S. Pat. No. 5,692,748 to Frisco et al. describes a card shuffling device containing free-swinging weights on pivoting arms that applies pressure to the top of stacks of cards that are to be mixed. The lowest card in each stack is in contact with a feed roller that propels the card horizontally, one at a time into a center mixing chamber. As described in Frisco, each of the first and second chambers 34, 36 has an arm 52 pivotally mounted at one end by a pivot 54 to the housing 12 and having at the other end a foot 56. As described therein, when cards are cut and deposited into the first and second chambers 34, 36, the arms 52 pivot as the cards 30 are urged over the front barriers 42 into their nested positions in the first and second chambers 34, 36. As nested on the floors 40 of the first and second chambers 34, 36, the arms 52 remain in contact with the top of the cards 30 to impose a vertical load on the cards 30 to urge them to be contacted by the wheels 48a, 48b. Proximate the foot 56 of each arm 52, a weight 58 is provided on each of the arms 52. These weights on pivoting arms apply pressure through the stack(s) of cards to assure traction against a pick-off roller at the bottom of the stack.

U.S. Pat. Nos. 6,655,684, 6,588,751, 6,588,750 and 6,149,154 to Grauzer et al.; U.S. Pat. Nos. 6,568,678 and 6,325,373 to Breeding et al.; and U.S. Pat. No. 6,254,096 to Grauzer describe a shuffler having a "free-floating," rolling weight that slides along a declining card support surface, toward a set of feed rollers to provide increased force on the

rollers to assist in advancing cards. The references also disclose sensors for detecting the presence of cards in a delivery tray or elsewhere.

U.S. Pat. No. 6,637,622 to Robinson describes a card delivery device with a weighted roller for assisting in card removal. A weighted cover is provided on the delivery end of the dealing shoe, covering the next card to be delivered.

U.S. Pat. No. 5,722,893 to Hill et al. describes the use of a weighted block for urging cards toward a discharge end of a shoe. The block provides a force against the cards. The block triggers a sensor when the shoe is empty. The reference specifically states: "In operation, a wedge-shaped block mounted on a heavy stainless steel roller (not shown) in a first position indicates that no cards are in the shoe. When the cards are placed in the shoe, the wedge-shaped block will be placed behind the cards and it and the cards will press against the load switch."

U.S. Pat. No. 5,431,399 to Kelley describes a bridge hand forming device in which cards are placed into an infeed area and are randomly distributed or distributed in a predetermined manner into four separate receiving trays. A weight is shown placed over the cards in the infeed area.

It would be desirable to provide structures and methods to apply a force to individually fed cards to assure consistent feeding, but only when the weight of the stack of cards is insufficient to provide adequate contact with the card feeder to consistently feed cards. It would be desirable for such a mechanism to be retractable so as to not interfere with card loading. It would also be desirable to provide a structure and methods that assist in temporarily retaining cards in a position that enables consistent and accurate card handling.

BRIEF SUMMARY

The present invention is a card weight that is pivotally engaged to a structure of a card handling device to provide force against the top of a vertically disposed stack of cards. In a preferred form of the invention, the card weight engages a top card in the stack only when the weight of the stack becomes insufficient to provide adequate contact between the lowermost card in the stack and a card feeder to assure accurate card feeding. A processor determines when the weight engages a top card and controls a drive mechanism that applies a force to the top card, and maintains the force as the cards are fed. Pivoting arms of the present invention may be pivotally mounted to a stationary portion of the card handling device, such as a support frame, or may be mounted to movable components, such as a support structure on a movable elevator that maintains a vertical alignment of a stack of cards as the card stack is lowered into position for shuffling.

Devices of the present invention are particularly useful in assuring accurate feeding of cards from a card feeding area into another area of the device. In some embodiments, pivotal arms of the present invention are integrated into the card shuffling structure, preventing unwanted movement of cards while the cards are being temporarily stored or suspended during shuffling.

Movable weights of the present invention are provided in the form of pivoting arms, and are preferably motor-driven. Sensors used in association with movable weights of the present invention provide signals indicating at least one of a number of cards remaining in the card feeding area, a number of cards fed, weight position, an absence of cards, a presence of cards, a percent shuffle completion or combinations thereof.

In one form of the invention, the weighted arm is retractable. Retractable weights in a retracted position advantageously move out of the card storing area, and avoid interfering with card loading and/or positioning of the cards.

Movable weights may be pivotally attached at a point significantly below the elevation of the top of a complete stack of cards in a card input area of the device. For example, if the card handling device is a multiple deck shuffler, a complete stack of cards might be a six- or eight-deck stack. Activation of a driving mechanism that causes the weight to engage a top card is preferably made in response to an indication of a number of cards left in the card storing area, a number of cards fed from the card storing area, a height of the stack of cards remaining in the card storing area, a percentage feeding completion, a percent shuffle completion or combinations thereof. In this manner, the movable weight is only used when the stack height is smaller, and the weight of the cards can no longer provide a sufficient force between the lowest card in the stack and the feed rollers to assure accurate feeding of individual cards. In one form of the invention, the pivoting arm is driven during card feeding so that an approximately constant force remains on the cards as they are fed.

In some embodiments, pivotal arms are used to retain groups of cards in other storing areas within the card handling device. For example, when cards are shuffled by randomly selecting a point in a vertical stack of cards, gripping cards above the selected point, lowering cards and/or the elevator below the selected point and inserting cards into a gap created beneath the gripped cards, a pivotal arm may be used to prevent cards from popping upwardly out of the grippers. Pivotal arms prevent unwanted movement of cards but normally only contact cards that are moving in an unwanted manner.

A method of handling playing cards is disclosed. The method comprises the step of positioning a vertically disposed stack of playing cards into a card storing area of a card handling device. A card moving system is provided. The card moving system moves cards individually out of the card storing area and into a second area from the bottom of the stack. According to the method, at least one parameter is measured, the at least one parameter is selected from the group consisting of: a number of cards fed from the card storing area, a number of cards remaining in the card storing area, a height of the stack of cards in the card storing area, a percentage feeding completion, or a percentage shuffle completion. When a predetermined value of a parameter is measured, the method includes providing a force to an uppermost card in the stack in the card storing area, increasing a force between a lowest card in the stack and the card moving system.

A method of handling playing cards is disclosed. The method comprises a step of positioning a plurality of stacked cards in a card handling area of a card handling device. The method also includes the steps of selecting a location to divide the stacked cards and creating a gap in the stacked cards at the selected location by suspending all cards above the selected location in the stacked cards. When a number of suspended cards is at or below a predetermined number, the method includes rotating a pivotal arm so that the arm is positioned proximate to and above a top card in the suspended cards to prevent cards from moving out of suspension.

BRIEF DESCRIPTION OF THE DRAWINGS

FIG. 1 shows a first side elevational view of a first exemplary card handling system of the present invention.

FIG. 2 shows a second side elevational view of the first exemplary card handling system.

FIG. 3 shows a front elevational view of a second exemplary card handling device of the present invention.

FIG. 4 shows a first side elevational view of the second exemplary card handling device of the present invention.

FIG. 5 shows a rear elevational view of the second exemplary card handling device of the present invention.

FIG. 6 shows another front elevational view of the second exemplary card handling device of the present invention with a pivotal weight arm rotated into a card-contacting position.

DETAILED DESCRIPTION

15

Playing card handling devices of the present invention are disclosed. The device comprises a card storing area that supports a stack of playing cards, the card storing area having a playing card support surface. The playing card handling device has a card removing system that removes playing cards individually from the bottom of the stack. A pivoting arm is automatically moved by a motor between at least two positions, wherein in a first position the end of the arm opposite a pivot is disengaged from a playing card at the top of the stack and in a second position the end of the arm is engaged with a playing card at the top of the stack. The device also includes a processor that directs movement of the pivoting arm between at least a first and second position when information is known to the processor that a predetermined number of cards is present in the card storing area of the card handling device. The processor additionally controls a drive mechanism, such as a stepper motor, to continue to move the pivotal weight in a manner that retains a force on the cards as the cards are fed.

Card handling devices of the present invention may include card dispensing shoes, automatic card shufflers, card set verification devices, card marking devices, card decommissioning devices, card sorting and packing devices and any other type of known card handling device. A card shuffling system may be present within the playing card handling device.

Pivotal weights of the present invention may be positioned in the card infeed area of a card handling device. A preferable movable weight is a pivotally mounted pivoting arm. Card storing areas may comprise card infeed areas for inserting cards. Other card storing areas may be intermediate storage areas within the card handling device. For example, when the card handling device is a shuffler, one or more temporary card storing areas may be located within the card shuffler.

In one embodiment of the invention, the processor causes the pivoting arm to rotate into a card contacting position when a predetermined number of between 8 and 20 cards remain in the card storage area. Prior to delivering the last 55 8 to 20 cards, the pivoting arm remains disengaged from the top card in the stack. It is to be understood that the weight continues to rotate during card feeding to maintain a force between the cards and a card feeder.

In some embodiments, the card handling device includes a card removing system and the card removing system comprises a pick-off roller. The movement of the pivoting arm into the engaged position applies pressure against a playing card at the top of the stack and also provides force between a lowest playing card in the stack and the pick-off roller during card feeding. Card handling devices of the present invention may include one or more sensors to measure at least a position or a degree of rotational position

of the pivoting arm, or the number of cards fed, a number of cards remaining, a percent shuffle completion, and the like. Devices of the present invention may alternatively include a counter for maintaining a count of playing cards in the playing card storing area during operation of the device.

Card handling devices of the present invention are processor controlled. The processor may cause the pivoting arm to pivot into an engaged position when a card count reaches a predetermined threshold amount, such as between 8 and 20 cards, and preferably about 10 cards. The processor of examples of the invention may be in communication with at least one sensor. For example, a card present sensor in a discharge tray or a pivoting arm position sensor may provide signals to the processor and use the signals to determine when to activate the pivoting arm, or the processor is in communication with a device that counts cards fed, or cards remaining in the infeed tray.

Playing card handling devices of the present invention may include a shuffling system within the playing card handling device, wherein the shuffling system comprises a playing card collection area where cards are moved individually from a playing card infeed area to the playing card collection area, and a pivoting arm is located in the playing card infeed area, wherein the pivoting arm moves automatically from an engaged position to a disengaged position when the card infeed area is empty, and moves from the disengaged position to the engaged position when a number of cards in the card infeed area falls to a predetermined number. In some embodiments of the invention, a sensor sends a signal to the processor indicating a number of playing cards remaining in at least one storage area of the playing card collection area and when that number of playing cards in the at least one storage area of the playing card collection area is a predetermined number, the pivoting arm moves to a second engaged position. Once engaged, the arm continues to pivot in response to being driven while cards are continually fed.

When the card handling device is a card shuffler, a set of grippers may be provided in the card collection area. The shuffler may further comprise a stationary card feeder and an elevator, wherein cards are elevated to an elevation of the grippers and the grippers grasp card edges of a group of cards, and when the elevator is lowered, at least one card is suspended and a gap is created below the suspended at least one card and a card support surface of the elevator or any cards on the elevator for insertion of a next card. Exemplary shufflers may be processor controlled, and may further be equipped with a random number generator to randomly determine a number of cards to be suspended by means of the grippers. The processor may be configured so that when the random number generator provides a number of suspended playing cards equal to or less than a predetermined number, the processor directs a pivoting arm to rotate so that an end of the arm distal from a pivot point moves into a position proximate to and above a top of the uppermost suspended playing card or cards.

The present invention may also be characterized as a card handling device that includes a card infeed area that supports a stack of playing cards that has a playing card support surface. The card handling device includes a card removing system that removes playing cards individually from the bottom of the stack and delivers cards into a playing card collection area. The playing card collection area is a portion of the device where playing cards are received one at a time after being removed individually from the bottom of the stack. A pivoting arm is provided that moves between a first position where a distal end of the pivoting arm is not in

contact with any playing cards in the playing card collection area and a second position where the distal end of the pivoting arm is in contact with a top card in the playing card collection area. A motor drives the pivoting arm causing the arm to continue to rotate during card feeding. A processor provides signals to the motor to move the pivoting arm between the first position and the second position in response to information received from a playing card counting system. The present invention also includes a playing card counting system that identifies total numbers of playing cards in at least one area in the playing card collection system.

In some embodiments, the playing card system comprises a random number generator that provides a random number of cards to be separated from an entire set of cards as an uppermost subset of playing cards, and it is the random number of playing cards in the uppermost subset of playing cards that is compared to a predetermined number of playing cards to determine whether the pivoting arm should be moved into a position proximate a top surface of the suspended cards. In other embodiments, the pivoting arm is moved into a position proximate the suspended cards regardless of card count or other sensed information.

A playing card handling device is disclosed, comprising a card infeed area that supports a stack of playing cards that has a playing card support surface. A card removing system that removes playing cards individually from the bottom of the stack is provided. A playing card collection area is provided where playing cards are received one at a time after being removed individually from the bottom of the stack. A first pivoting arm is movable between a first position where a distal end of the pivoting arm is not in contact with any playing cards in the playing card collection area and a second position where the distal end of the pivoting arm is in contact with a top card in the playing card collection area. According to the invention, a motor is provided to pivot the first pivoting arm. Pivoting preferably continues during card feeding. A processor in the card handling device provides signals to the motor to move the first pivoting arm between the first position and the second position.

A playing card counting system that identifies total numbers of playing cards remaining in at least one area in the playing card collection system is provided. The playing card counting system comprises a random number generator that provides a random number of cards to be separated from an entire set of cards as an uppermost subset of playing cards, and it is the random number of playing cards in the uppermost subset of playing cards that is compared to a predetermined number of playing cards to determine whether a pivoting arm should be rotated to a position proximate a top separated card in the first position or in the second position.

The present invention includes a method of handling playing cards. The method comprises a step of positioning a vertically disposed stack of playing cards into a card storing area of a card handling device. A card moving system is provided that moves cards individually out of the card storing area and into a second area from the bottom of the stack. Included in the method is a step of measuring at least one parameter selected from the group consisting of: a number of cards fed from the card storing area, a number of cards remaining in the card storing area, a height of the stack of cards in the card storing area and a percent of cards fed. According to the method, when a predetermined value of a parameter is measured, a force is provided to an uppermost card in the stack in the card storing area, increasing a force between a lowest card in the stack and the card moving system. This added force remains on the cards during

feeding, and assures accurate transfer of cards out of the card storing area of the card handling device.

In a preferred embodiment, the first area is a card infeed tray and the second area is a card shuffling area. Cards stored in the card shuffling area may be stored temporarily as part of a shuffling process. When cards are temporarily stored in the second area, methods of the present invention include the step of shuffling the cards. In some embodiments of the invention, shuffling can be accomplished by separating the stack in a randomly determined location, creating a gap in the stack at the randomly determined location, inserting a card, and then repeating the steps of randomly determining a location, creating a gap and inserting a card.

Methods of the present invention include methods of handling playing cards, comprising the step of positioning a plurality of stacked cards in a card handling area. According to the method, a location to divide the stack is selected. Preferably, this selection step is accomplished by means of a processor, and the use of a random number generator in communication with the processor. Random number generators may be in the form of software, hardware or the combination of software and hardware. According to one of the methods, a gap is created at the selected location by suspending all cards above the selected location in the stack. When a number of suspended cards is at or below a predetermined number, a pivotal arm is rotated to a position proximate a top surface of a top card in the suspended stack to prevent cards from moving out of suspension. In some embodiments, the gap created when the cards are suspended is accomplished by raising the stack of cards by means of an elevator to a stationary pair of opposing grippers. At least one of the grippers in a gripper pair moves horizontally to grasp the card edges. If too few cards are in the grippers, the cards bow and have a tendency to pop out of the grippers. By applying a blocking force above to a top card face, cards can be retained in the temporary storing location. Without the pivotal arm in place, if cards do pop out of the grippers, they may become vertically aligned and fall into a lower portion of the card shuffling area, where they remain until the cards are manually removed.

When the card handling device includes a shuffling mechanism, according to a method of the present invention, it is desirable to provide a step of providing a stack of cards in a card storing area, and moving cards individually into the card handling area of the shuffling mechanism. Cards placed in the card handling device may be fed individually from a bottom of a vertically positioned stack in the card storing area.

According to one of the methods, when a gap is created in the cards to allow the insertion of the next card, an elevator may be provided to raise the stack to a predetermined elevation so that stationary grippers can grasp an upper portion of the stack. Advantageously, an elevator may be provided to raise the stack. The predetermined location may be randomly selected by the processor, or the random number generator that is in data communication with the processor.

According to a preferred method of the present invention, a gap is created in the stack by elevating cards to a preselected elevation, grasping a number of cards above the selected location and then lowering the cards that were not grasped to create an opening for insertion of a next card. An elevator is preferably used for raising and lowering the cards. The pivotal arm may be rotated back to a retracted position either prior to, during or after grippers release the cards. Preferably, the pivotal arm is rotated back just prior to releasing cards from the grippers.

Structures of the present invention may be used in combination with a variety of card handling devices, such as mechanized card shoes, card set checking devices, automatic card shufflers, card sorting devices, card decommissioning devices, and the like. Although preferred structures are used in connection with substantially vertical card stacks with gravity feed systems, pivotal arms of the present invention may be used to apply forces to cards that are in horizontally aligned stacks, and stacks that are positioned at an angle with respect to the vertical. For example, it might be advantageous to provide a card stack that is tipped 5 degrees to 10 degrees with respect to the vertical so that manual card stack insertion and alignment is made easier.

Structures of the present invention are useful to incorporate into a card input or infeed section of a card handling device, or in other areas of the device that hold cards, regardless of how much time the cards remain in a particular area of the card handling device. For example, pivotal arms of the present invention may be used to assist in accurately retaining cards in a temporary storing area, where cards are stored as part of a shuffling process. Other storage areas hold cards in a card input area, in a completed processed set area, and in other temporary storage locations, regardless of the duration of the storage time. It can be readily appreciated that stacks of cards may be formed in various locations within the card handling device and the present technology may also be used to move cards from internally formed stacks within the device to another area of the device, such as an output tray, for example.

Although structures and methods of the present invention may be applied to vertically disposed stacks of cards that retain card surfaces in a horizontal plane in adjacent card face to card back relationship, the invention may be used to facilitate card movement from stacks that are horizontally oriented, or are oriented at an angle with respect to the horizontal or vertical. For example, structures and methods of the present invention also may be used in connection with delivering cards on a declining surface in a shoe.

Suitable shuffling mechanisms that may be used in connection with the present invention encompass many different types of shuffling technologies, such as random card ejection technology (i.e., U.S. Pat. No. 7,066,464 to Blad et al.), random distribution of cards into compartments within a stack of cards (i.e., U.S. Pat. No. 6,254,096 to Grauzer), distribution of cards into a circular carousel of compartments (i.e., U.S. Pat. No. 6,659,460 to Blaha et al.), distribution of cards into a fan array of compartments, distribution of cards into an opening that was randomly selected and then created in a stack (i.e., U.S. Pat. No. 6,651,981 to Grauzer et al.), etc. The disclosure of each of these patents is hereby incorporated herein by reference in its entirety.

In a first embodiment of the present technology, as shown in FIG. 1, a set of playing cards 6 is placed as a vertically disposed stack into a card infeed area 5 of a card handling device. Although the cards 6 are vertically stacked (with the face of each card being in a horizontal plane) within the card infeed area 5 in this embodiment, the stack of cards 6 may also be slightly angled (e.g., +/-30 degrees from horizontal). The cards 6 are stacked in the card infeed area 5 and then the cards 6 are removed one at a time from the bottom of the set of cards 6 by means of pick-off rollers 22, 23. Cards 6 are individually moved to speed-up roller pair 28, 30 where they are delivered into a shuffling mechanism (not shown). An exemplary shuffling mechanism for randomizing the stack of cards 6 is described in U.S. Pat. No. 6,651,981 to Grauzer et al. Preferably, the cards 6 are placed in the card infeed area 5 face down, so that no card value is exposed to the players

or dealer, but this is not of functional importance to the practice of the present technology.

Systems that move cards out of a substantially vertically disposed stack of cards from the bottom of the stack are referred to in the casino supply industry as "gravity feed" systems. In gravity feed systems, playing cards are removed from the bottom of the stack, and the weight of the stack applies a downward force to the card moving structure. Typically, a friction wheel 22 (referred to as a pick-off roller) extends upwardly and into the bottom of the playing card input chamber, and into contact with a lowermost card in the stack. Rotation of the pick-off roller 22 provides a driving force against the playing card, forcing the playing card horizontally out of the card input chamber and toward the shuffling area.

A pivoting arm 8 is fixedly mounted to a frame 60 at pivot point 10. In a card engaging position, as shown in FIG. 1, roller 12 contacts an upper surface of the top card in the stack of cards 6, applying a downward force on the stack of cards 6. The pivoting arm 8 is rotated by means of a stepper motor 32 that drives pulley 36, which in turn drives pulley 38 by means of belt 64. As shown in FIG. 2, the pivoting arm 8 in a retracted position is clear of the card infeed area 5 when in a card disengaging position. The pivoting arm 8 does not interfere with card loading, because the entire pivoting arm 8 is removed from the card infeed area 5.

Embodiments of the card handling device of the present disclosure incorporate at least one sensor to indicate the position or a degree of rotation of the pivoting arm, or incorporate other sensors to indicate a number of cards remaining in the card storing area. The position of the movable weight in some instances can be used as an indication of whether or not cards are present in the card storage area. In other embodiments, a card present sensor is also provided in the card storing area to indicate an absence or presence of one or more cards.

Embodiments of the present invention are used in connection with card handling devices that maintain a count of playing cards in the playing card infeed area during card handling operation of the device. Card handling devices are preferably processor controlled. The processor may be in communication with at least one sensor, such as a pivoting arm position sensor, a card present sensor, a card counter or other sensor. The processor is capable of determining that a predetermined maximum number of playing cards has been reached after removal of a portion of the set of playing cards from the playing card infeed area. In response to meeting this condition, the processor causes activation of a drive mechanism to pivot the pivoting arm into a card engaging position. Pivoting arms of the present invention advantageously apply more force to a top card in the stack than known card weight systems. In addition to the weight of the arm, additional forces are applied by the drive system during card moving.

Within the card handling device, there may be a shuffling system that moves cards individually from the playing card infeed area into a card shuffling mechanism. During shuffling, cards may be temporarily stored in a temporary card storing area. A random number generator determines a location in the stack to suspend cards. In most instances, the stack is divided into two sub-stacks. In other instances, all of the cards, or none of the cards are suspended. This determination, in turn, determines how many cards are temporarily stored in the area of suspension. When a threshold number of cards or fewer is present in the temporary storing area, a pivotal arm is activated to move the arm over the top of the suspended cards, close enough to the cards to prevent

the cards from flipping over if a card pops out of the grippers. In one embodiment, this proximate relationship is a few card thicknesses. In other examples, the distance is between one card thickness and a dimension of a card length or width. During operation, the pivotal arm provides a barrier to stop cards from flipping over. Unless cards pop out of the grippers, no contact is made between the arm and the cards. For example, a vertical stack of cards may be temporarily stored in a pair of spaced-apart horizontally reciprocating grippers and a pivotal arm may be provided above the gripped stack to stop cards that have popped out of the grippers from flipping over and falling vertically down the side of the stack. A suitable gripper set grasps cards by moving horizontally while the structure is fixed in the vertical direction. Shortly before, during or after the gripper is released, the processor directs the pivotal arm to disengage the cards. In other embodiments, the pivotal arm remains in the engaged position when the grippers release the cards.

The pivotal arm of the present invention may be positioned over cards in the grippers at all times, or when relatively few cards are gripped. When there are a small number of cards in the grippers, the force of the grippers is more likely to cause cards to bow and pop out and flip. It may be desirable to cause the flipper to move into a "bracing" position when a threshold number of cards or fewer are gripped.

For example, a threshold number of gripped cards may be ten cards. The number of cards defining the threshold amount can vary, depending on the type of cards, card weight, and frictional characteristics of the card. For example, plastic cards are typically thicker and more rigid than paper cards. In that instance, the threshold number of cards could be lower than when the device is programmed to process paper cards of a certain manufacturer. In general, suitable threshold amounts for a variety of playing cards used in U.S. casinos would be between eight and fourteen cards, and preferably about ten cards.

When the random number generator selects a location in the stack to separate the cards, the processor determines how many cards are retained in the grippers. Alternatively, the processor selects a card in the stack and determines whether that card and the cards above that card should be gripped. Or, the selected card is determined to be part of the lower sub-stack. If the number of gripped cards is less than or equal to ten cards, for example, the pivotal arm is activated to move into a bracing position.

Referring back to FIGS. 1 and 2, the use of a pivoting arm 8 with a center of rotation of the pivoting arm 8 that is below a point that is spaced above, and preferably at least 15 mm above, the card support surface in the card infeed area 5 is illustrated. The center of rotation may alternatively be located above the playing card support surface by at least 18 mm, at least 20 mm or at least 25 mm or more. Preferably, the pivot point 10 is also spaced apart from the card infeed area 5. The ability to provide this elevation of the pivot point 10 of the pivoting arm 8 in relation to the playing card surface allows for a lower height to the system, better consistency of weight against the cards, and the like. The relative elevation is provided by having a pivoting arm 8 that extends above the pivot point 10 on one end of the pivoting arm 8 and also above a playing card contact point 9 on the other end of the pivoting arm 8. This creates an elevated middle area or recess in the pivoting arm 8, which can extend over the edge of the playing cards 6 in the card infeed

11

area **5** to avoid contact with those cards. In other words, the pivoting arm **8** of the pivotal weight is advantageously U-shaped.

A second concept developed herein is the use of a motor-driven pivoting arm **8** that controls the height of the contact point **9** and/or the force at the contact point **9** and/or the retraction/lowering of the pivoting arm **8** and/or other actions by the pivoting arm **8** with respect to the loading, unloading and shuffling process, including addressing any card jam events. FIG. 1 shows a sectioned or cutaway side elevational view of a playing card feeding portion **2** of a playing card handling system. The height of a set of cards **6** (e.g., a single deck of cards is illustrated) is shown in the playing card receiving or card infeed area **5**. A pivoting arm **8** is shown with a roller **12** pivotally mounted about rotational shaft **14** at the contact end of the pivoting arm **8** resting on the top of the set of cards **6**. This may represent a locked or controlled position of the pivoting arm **8**. The pivoting arm **8** pivots about pivot point **10** and the roller **12** pivots about rotational shaft **14**. A dashed line **16** is shown between the pivot point **10** and the lower surface of the roller **12**. As can be seen, this dashed line **16** intersects the height of the playing cards **6**, which would mean that the traditional straight weighted arm (as taught by Frisco, above) would rest against the edge of the cards and possibly interfere with, damage or mark the cards. As is shown in FIG. 1, there is a significant gap **18** above the dashed line **16** and the height of the set of playing cards **6** in the card infeed area **5**. This structure prevents the need for elevating the pivot point **10** of the pivoting arm **8** above the height of the uppermost card in the stack of cards **6**. When the pivoting arm **8** and pivot point **10** have to be so elevated, the overall height of the shuffler is increased. Additionally, other functioning parts of the arm system, (i.e., the belts if used, drive wheels and the shaft, for example) may be exposed and subject to damage from the exposure.

A bottommost playing card **7** is driven by pick-off rollers **22, 23** through an outlet slot **24** in the bottom of the playing card infeed area **5**. The playing card **7** driven through the slot **24** then engages speed-up rollers **28** and **30**, which form a nip **26** that moves the playing card **7** into the shuffling area of the shuffler (not shown). A motor **40** drives shaft **42**. Shaft **42** rotates, causing sheaves **44, 46** and **48** to rotate. An endless member **50** contacts sheaves **44, 46** and **48**.

A stepper motor **32** is provided to drive a drive wheel **34** with drive belt **64** that also engages pulley **38**, causing the weighted pivoting arm **8** to pivot. Once the last card exits the card infeed area **5**, the pivoting arm **8** rotates downwardly in a direction of arrow **52** into a retracted position. In the retracted position, as shown in FIG. 2, the pivoting arm **8** is completely free of the card infeed area **5**. Cards can be manually loaded without any interference from the pivoting arm **8**.

After the next group of cards is inserted into the card infeed area **5**, the pivoting arm **8** continues to rotate in a clockwise direction, as shown by arrow **54** (FIG. 2), until the roller **12** comes back into contact with the top card in the next stack. Alternatively, the pivoting arm **8** rotates in an opposite direction to a position that is free of the card infeed area (not shown). The card weight advantageously retracts and does not interfere with the loading of cards. A card present sensor **56** may send a signal to the processor (not shown) that in turn actuates stepper motor **32** to rotate pivoting arm **8** into the "card engaged" position.

Operation of the pivoting arm **8** may be controlled by a processor (not shown) and/or react to sensors or be free in its pivoting. When the pivoting arm **8** has the gap **18** built in,

12

the pivoting arm **8** may pivot and retain cards under its own weight. Because of the initial elevation of the pivoting arm **8** (as shown by the angle of dashed line **16** with respect to the horizontal), the pivoting arm **8** will initially (under its own weight) pivot first toward the horizontal and then slightly below the horizontal. The contact point **9** between the roller **12** and the top surface of the uppermost playing card will also move from a non-centered position toward a more centered position, as the height of the stack of playing cards **6** changes. This orientation of the pivoting arm **8** with a roller **12** thereon reduces damage to surfaces of the cards that are contacted by the roller **12**.

When the pivoting arm **8** is motor driven, an intelligent drive system (as with a processor, microprocessor or computer, with "processor" used generically) may assist in driving the positioning of the pivoting arm **8** and apply contact pressure between the pivoting arm **8** and the top of the set of playing cards **6** in the card infeed area **5**. The application of pressure can be accomplished a number of ways. For example, the processor may instruct the stepper motor **32** to move a defined number of steps or positions for each fed card.

One mode of operation of the intelligent drive system may include some or all of the following features. When no playing cards are present in the chamber (signals or data of which may be obtained from card present sensors or cameras), the processor may direct the pivoting arm **8** to be rotated into a retracted position to facilitate depositing of the playing cards by hand. When the processor is provided with information such as signals or data indicating that playing cards **6** are positioned in the card infeed area **5**, the pivoting arm **8** is rotated (clockwise in FIG. 1) until contact is sufficiently made with the top of playing cards **6**. This sensing may be accomplished in numerous ways, as with a contact sensor (not shown) in the rotational shaft **14**, tension reduction sensed in the pulley **36** through the stepper motor **32**, cameras or optical sensors (not shown) in the card infeed area **5**, and the like. Once contact is made, the pivoting arm **8** may remain under tension by the drive system or become free in its rotating by disengaging gearing or pulleys (e.g., pulley **36**) driving the pivoting arm **8**. Alternatively, upon removal of cards, the processor will adjust the tension in the pulley **36** to adjust the contact force of the roller **12** against playing cards **6**. This adjustment may be done continually, periodically or at specific event occurrences, such as the movement of a single card, the movement of a specific number of cards out of the card infeed area **5**, or the like. The force applied by the roller **12** to the top playing cards should usually be sufficient that removal of a single card from the bottom of the set of cards **6** will not completely remove the force applied by the roller **12**.

The system may also indicate the absence of playing cards in the card infeed area **5**. For example, a card present sensor **56** may indicate that no cards are in the card infeed area **5**. The system may utilize the same sensors that indicate the presence of cards in the playing card infeed area **5** to indicate the absence of cards in the card infeed area **5**. Alternatively, the arm itself may be associated with various sensors to indicate the absence of playing cards in the card input chamber. For example, when there are no cards in the chamber, the arm may continue to rotate clockwise to a "retracted" position. The arm (as associated sensors or systems that measure the degree of rotation of the arm) may be preprogrammed or trained to recognize the lowest position of the arm with a single card in the chamber. When that

position or degree of rotation is subsequently exceeded, a signal will be sent to send the pivoting arm **8** to the lowest position (shown in FIG. 2).

As noted above, the end of the arm is provided with a roller, but a low-friction surface may also be provided in place of the roller. For example, a smooth, flat, rounded edge with a polymeric coating (e.g., fluorinated polymer, polylloxane polymer, polyurethane, etc.) can provide a low-friction surface that will slide over the playing cards without scratching the cards.

Some of the properties of the exemplary pivotally mounted card weight arm with the roller or glide surface thereon are: essentially downward (toward the cards) a free-swinging or controlled arm, with a lower edge gap that extends over edges of playing cards when the arm is elevated; a sensing device identifying the position of the arm along its path of movement, the sensed position including sensing of a position of the arm or contact of the arm, indicating the presence, absence or approximate amount (number) of cards in the card infeed area, the sensor signaling a processor that commands a motor attached to a belt that can motivate the weighted arm into a contact position and a retracted position; and an automatic sequence that rotates the weighted arm into a retracted position to allow insertion of additional cards into the shuffler.

Although the pivoting arm may move freely about the pivot point, in one form of the invention, the pivoting arm is spring-loaded such that a force must be applied to the arm in order to raise the arm high enough to insert cards. In another form of the invention, the card feeding device includes a computer-controlled drive system. An exemplary drive system includes a motor that rotates the pivoting arm about the pivot point (or pivotal shaft). In a first engaged position, a contact end of the pivoting arm applies a downward force to the stack of cards. The drive, the weight of the arm, or both apply a downward force to the cards. When the pivoting arm is rotated by a motorized drive system, the motor positions the pivoting arm to apply pressure against the card at the top of the stack.

Sensors may be provided to signal the microprocessor to instruct the drive system to rotate the pivoting arm. An example of one sensor is a position sensor located on the pivotal shaft. This sensor provides an indication of the position or degree of rotation of the pivoting arm. Each provided sensor is in communication with the processor. The processor may also instruct the motor to alter the position of the pivoting arm upon receiving a sensor signal. Another example of a suitable sensor is a card present sensor located on or beneath the card support surface.

One preferred drive motor is a stepper motor. The stepper motor may rotate in two directions or just in a single direction. When the motor rotates the pivoting arm in a single direction, the pivoting arm is capable of moving from a recessed position back into a card engaging position without interfering with card loading. Preferably, the pivoting arm is completely concealed within an interior of the machine when in the recessed position. When in the recessed position, no part of the pivoting arm extends into the card infeed area, leaving the area free for typical card loading.

Reference to FIGS. 3 through 6 shows an alternative embodiment that employs the technology of the present invention. FIG. 3 shows a frontal elevational view of shuffler **100** with the housing removed. The shuffler **100** has a support structure **102** adjacent to a card infeed area **110** of the shuffler **100**. Cards (not shown) are placed within card receiving chamber **104** through an access opening (not shown) in an upper surface of the shuffler **100** and the card

stack is seated at its lowest level **112** within the card receiving chamber **104**. The lowest level **112** represents a card support surface. As cards are removed one at a time from the card receiving chamber **104**, and moved to a shuffling area **122**, the number of cards removed is counted. The number of original cards input into the shuffler **100** is known (by preprogramming or user input at the time of the input), and by deducting the number of cards removed from the card receiving chamber **104**, the number of cards remaining in the card receiving chamber **104** are known. A processor **120** is preprogrammed to direct activation and position of a card weight motor **108**, which card weight motor **108** causes a card weight arm **106** to rotate (into the direction of the paper) about axis **109** from its raised position (shown) to a card engaging position (not shown) where it presses against the flat top of cards in the card receiving chamber **104**. The mass of the arm **106** and, preferably, also light spring pressure from an arm extension or extended spring element **114**, applies force from the top of the predetermined number of cards in the card receiving chamber **104** through the cards, to a lowermost card in the card receiving chamber **104** so that the lowermost card is pressed against a first pick-off roller **116a**. A random number generator module **118**, described in more detail below, is in communication with the processor **120** and is also shown in FIG. 3.

FIG. 4 shows a side elevational view of the shuffler **100** with the housing removed. Above the card receiving chamber **104** where playing cards are fed into the shuffler **100** is a pivoting lid **124**. An elevated pivoting card weight arm **106** is shown in a retracted or "disengaged" position **106a**, outside of the card receiving chamber **104**. Also shown in FIG. 4 is the same card weight arm **106**, or pivotal arm, in a lowered or "engaged" position **106b**. Of course, these two positions **106a**, **106b** cannot be present at the same time, as there is a single arm (106 of FIG. 3), but these views show the movement of the arm **106** between positions **106a** and **106b**. The spring element **114** is shown in contact with the first pick-off roller **116a** and not in contact with the axially aligned second pick-off roller **116b**. One suitable spring is formed of plastic. Other materials, such as metallic materials, may be used to form a spring. The lowest level **112** of the card receiving chamber **104** can be seen with no playing cards in the card receiving chamber **104**. This is why the spring element **114** is in contact with the pick-off roller **116a**. All reference numerals in FIG. 4 that are the same as reference numerals in FIG. 3 show similar components of the shuffler **100**. When a predetermined number of cards (or fewer) are left in card receiving chamber **104** during card feeding, card weight arm **106** moves from the card disengaged position **106a** to the card engaged position **106b**.

FIG. 5 shows a rear elevational view of the shuffler **100** with the housing removed. This view is opposite the view shown in FIG. 3. Card infeed area **110** is on the opposite side in FIG. 5. A card anti-flip arm **206** (also referred to above as a pivoting arm) is shown within the card shuffling or card collection area **200**. A motor **208** for the card anti-flip arm **206** is shown, the card anti-flip arm **206** being shown in an upright (inactive) position. All reference numerals in FIG. 5 that are the same as reference numerals in FIG. 3 or FIG. 4 show similar components of the shuffler **100**. In a preferred embodiment, when cards are present in grippers **220**, the card anti-flip arm **206** is moved to an active position (i.e., horizontal) to prevent cards from flipping over.

In another embodiment, when the random number generator module (e.g., **118** of FIG. 3) identifies to the processor (**120** in FIG. 3) that fewer than or equal to a predetermined number of playing cards are to be supported during shuf-

15

fling, the playing card anti-flip arm 206 will move from an inactive to an active position. The card anti-flip arm 206 will retract to the inactive position at a predetermined time, which may be as a card is inserted below the supported card(s), after the card has been inserted below the supported card(s) or after the supported cards are combined with the cards on an elevator or before another number of playing cards is supported.

FIG. 6 shows a side cross-sectional view of the shuffler 100 with the housing removed, in a plane that clearly shows the operation of the card anti-flip arm 206. In the retracted or inactive position 206a, card anti-flip arm 206 is outside of the temporary card collection area 200, and when rotated to an engaged position 206b, the card anti-flip arm 206 is substantially horizontal. A small number of playing cards 222 is shown supported by one of a pair of spaced-apart grippers 220. When that number of playing cards 222 is less than or equal to a predetermined number of playing cards (e.g., 3, 4, 5, 6, 7, 8, 9, 10, etc.), the card anti-flip arm 206 is moved to position 206b to prevent any cards that pop out of the grippers 220 from flipping, which could cause jamming of the shuffler 100, or expose a card within the shuffled set by flipping the wrong side (face side) up in the shuffled set of cards, or causing gripped cards to become vertically aligned.

In some embodiments of the invention, when there are relatively few cards in the shuffling area 200, the playing card anti-flip arm 206 will remain in the engaged position 206b for some number of cards being inserted. An elevator 224 (FIG. 6) that supports and lowers playing cards (not shown) that are not gripped by the grippers 220 is also shown. After the initial number of cards are present in the shuffling area 200 and the random number generator has not selected a number of cards to be gripped less than or equal to the second predetermined number, the playing card anti-flip arm 206 will return to position 206a. When the random number generator selects a number of cards to be gripped less than or equal to the second predetermined number, the playing card anti-flip arm 206 will return to position 206b to be positioned above the playing cards 222 supported by the grippers 220.

Although specific examples, sequences and steps have been clearly described, variations and alternatives would be apparent to those skilled in the art and are intended to be within the scope of the invention claimed.

What is claimed is:

1. A playing card handling device, comprising:
  - a housing;
  - a card handling area including a card support surface within the housing;
  - grippers for suspending at least a portion of a group of playing cards above the card support surface;
  - a pivotal arm mounted within the housing and movable between a disengaged position away from a playing card at a top of the group of playing cards and an engaged position above and spaced apart from a playing card at the top of the group of playing cards; and
  - a processor configured to initiate movement of the pivotal arm between the disengaged position and the engaged position responsive to information that a predetermined number of playing cards is to be suspended in the grippers.
2. The playing card handling device of claim 1, further comprising an elevator in the card handling area, the elevator configured to lower a remainder of the group of playing cards below an elevation of the grippers after suspending the at least a portion of the group of playing cards.

16

3. The playing card handling device of claim 1, wherein the grippers are stationary in a vertical direction and at least one gripper is configured to move in a horizontal direction.

4. The playing card handling device of claim 1, wherein the grippers are configured to apply a compression force to opposing sides of gripped cards, and wherein the pivotal arm is positionable above an upper surface of a top gripped card when the pivotal arm is in the engaged position.

5. The playing card handling device of claim 4, wherein the pivotal arm is movable to the engaged position when a number of the gripped cards is between one and fourteen.

6. The playing card handling device of claim 1, wherein the pivotal arm is movable from the engaged position to the disengaged position following insertion of a card into a gap in the group of playing cards.

7. The playing card handling device of claim 1, wherein the pivotal arm is substantially horizontal when in the engaged position and is substantially vertical when in the disengaged position.

8. The playing card handling device of claim 1, further comprising a sensing system configured to sense a presence of playing cards within the card handling area and send a signal to the processor programmed to initiate movement of the pivotal arm to the engaged position upon receipt of the signal.

9. A playing card handling device, comprising:

- a card infeed area;
- a card handling area comprising an elevator platform for supporting playing cards;
- a card moving system configured to direct movement of playing cards from the card infeed area to the card handling area;
- grippers for suspending one or more of the playing cards above the elevator platform;
- a pivotal arm within the card handling area, the pivotal arm positionable above the elevator platform and spaced apart from playing cards on the elevator platform when in an active position; and
- a random number generator for determining random locations for inserting additional playing cards into a group of playing cards on the elevator platform, the pivotal arm configured to move to the active position when a number of suspended playing cards is within a predetermined range.

10. The playing card handling device of claim 9, further comprising a playing card counting system configured to monitor a number of playing cards in the card handling area, wherein the pivotal arm is configured to remain in the active position until the number of playing cards in the card handling area reaches a predetermined number.

11. The playing card handling device of claim 9, further comprising at least one card sensor, the pivotal arm configured to move to the active position responsive to information received from the at least one card sensor indicating a presence of playing cards in the card handling area.

12. The playing card handling device of claim 9, wherein the card moving system comprises rollers for inserting individual playing cards from a bottom of a stack of playing cards in the card infeed area into a gap below the suspended playing cards.

13. The playing card handling device of claim 9, wherein the pivotal arm is configured to move to an inactive position after the suspended playing cards are combined with the group of playing cards on the elevator platform.

14. A playing card handling device, comprising:

- a card handling area including a support surface for supporting a stack of cards;

17

- a pivotal arm within the card handling area, the pivotal arm configured to move into and out of vertical alignment with the stack of cards during operation of the playing card handling device;
- a processor configured to direct movement of the pivotal arm responsive to information received by the processor; and
- a random number generator for determining a card insertion location in the stack of cards;
- wherein the processor is programmed to direct movement of the pivotal arm into vertical alignment with the stack of cards when a number of cards in a predetermined range are suspended above a remainder of the stack of cards.
- 15.** The playing card handling device of claim **14**, wherein the pivotal arm is positionable over a top card suspended above the stack of cards without contacting the top card when the pivotal arm is in vertical alignment with the stack of cards.
- 16.** The playing card handling device of claim **14**, further comprising grippers located below the pivotal arm, the

18

- grippers configured to grip one or more cards suspended above a remainder of the stack of cards to create an opening for insertion of a card.
- 17.** The playing card handling device of claim **14**, further comprising an elevator configured to raise the stack of cards to a card receiving area located at an elevation proximate a gaming table surface.
- 18.** The playing card handling device of claim **17**, wherein the pivotal arm is pivotally mounted to a support structure of the playing card handling device, the pivotal arm positionable outside the card handling area when the elevator raises the stack of cards.
- 19.** The playing card handling device of claim **14**, wherein an elongated portion of the pivotal arm is substantially horizontal when the pivotal arm is in vertical alignment with the stack of cards.
- 20.** The playing card handling device of claim **14**, wherein a portion of the stack of cards extends beyond a lateral extent of the pivotal arm when the pivotal arm is in vertical alignment with the stack of cards.
